UNITED STATES PATENT OFFICE.

CHARLES M. FEIST, OF SIOUX CITY, IOWA.

ECONOMIZER AND ADAPTER FOR BURNERS.

Application filed December 8, 1925. Serial No. 74,107.

This invention relates to an economizer and adapter for association with gas, oil and analogous burners, and the primary object of the same is to provide a simple device which may be readily mounted on a burner and adjusted to accommodate burners of varying diametrical extent or size and operating to prevent the heat flames from spreading and thereby concentrate the heat units and obtain the full benefit of the flame of the burner relatively to cooking utensils that may be disposed over the burner and the improved device.

A further object of the invention is to provide means particularly adapted for concentrating the heat energy from a burner relatively to comparatively small bottom portions of coffee or tea pots and similar receptacles and to shield the handles of such receptacles against contact and burning by the flames of burners which ordinarily flare upwardly outside of the area of the bottom portions of the receptacles, and also avoid waste of heat by causing the burner flames to be drawn inwardly towards the bottom of the cooking utensils that may be disposed over the burner.

With these and other objects and advantages in view, the invention consists in the preferred construction and arrangement of the attachment which will be more fully hereinafter described and claimed.

In the drawing:

Fig. 1 is a transverse vertical section through a burner and a portion of the grate above the same, showing the improved economizer and adapter applied to the burner below the grate and also illustrated in cross section.

Fig. 2 is a detail perspective view of the improved economizer and adapter.

Fig. 3 is an enlarged transverse vertical section through the joined extremities of the improved economizer and adapter and showing one means for fastening the same to permit adjustment of the attachment to accommodate burners of varying dimensions.

The numeral 5 designates a burner of usual or well known construction, to which is connected a fuel supply pipe 6, and over the burner at the usual elevation is a portion of a supporting grate, also commonly used in gas, oil and analogous stoves. The burner 5 may have any number of radiating arms or portions or consist of a hollow disk-

like body, both of the latter forms being common in the formation of oil, gas and similar burners, and at the top portion of the burner is a series of jet openings 8 for emission of the fuel and ignition of the latter.

The improved economizer and adapter as heretofore indicated is in the form of an attachment which is constructed in such manner as to be readily applied over the burner and held intact with the latter, it also being preferred to make the improved attachment adjustable so that the diameter thereof may be varied to fit burners of different sizes. The improved attachment consists of an upwardly projecting wall 9 continuing into an inwardly inclined or converged top flange 10. The top flange 10 is regularly crimped in an upward direction, as at 11, to strengthen the top portion of the attachment and also to form a plurality of flues, which will direct the flame and heat currents inwardly or concentrate the flame towards the open portions of the grate above. As shown, the corrugations formed by crimping the flange 10 are inclined, and this is one preferred construction. The upper flange 10 having the crimped formation or corrugations produced by the crimping operation will obstruct warping of the said upper flange, and furthermore, when the upper extremities 12 and 13 of the attachment are brought together and overlapped, the corrugations of the flange 10 will interlock and serve as a means for materially assisting in holding the said overlapped extremities in associated relation. Suitable fastening means may be used to connect the overlapped extremities or hold the latter against displacement from a desired overlapping extent, but it is also preferred that a fastening means be used whereby the adjustment of the diameter of the attachment may be readily modified to such an extent as to accommodate burners of various sizes. One means for holding the overlapped extremities 12 and 13 of the attachment in positive associated relation against movement consists of a wire 14, which is placed closely against the outer side of the wall 9 and continued upwardly over the crimped or corrugated flange 10 and has the ends thereof bent inwardly closely against the inner side of the overlapped extremity 13 and the upper portion of the flange 10 continuing from said overlapped extremity as clearly shown

by Fig. 3. Preferably, the upper edge of the attachment is located a short distance below the underside of the grate 7, and by this means the flame and heat energy are brought up close to the grate and concentrated on the bottom of the cooking utensil resting on the open portion of the grate over the burner and improved attachment. The improved attachment is made of suitable metal, preferably sheet iron, and in constructing the same the upper converged flange 10 may be crimped by running it through a suitable crimping machine and at the same time evenly bending the flange inwardly relatively to the wall or body 9.

The improved device will be found exceptionally advantageous in its use and will greatly economize in the utilization of fuel and give the best results from a heating standpoint relatively to cooking utensils that may be disposed thereover as well as protect parts of said utensils from burning by irregularly upwardly projected flames outside of the area of the bottom of the said utensils.

What is claimed as new is:

1. In an economizer and adapter for burners of the type specified, consisting of an upwardly and inwardly inclined body applicable over a burner and having an upper flange inwardly inclined at a greater angle than the body and crimped in an upward direction to strengthen the top of the economizer and also to form flame and heat flues, the extremities of the body and flange being separably overlapped to modify the diameter of the device as a whole.
2. An economizer and adapter for burners of the type specified, having an upper inwardly converged body and an upper flange inwardly inclined at a greater angle than the body and crimped, the extremities of the body and flange being separably overlapped to modify the dimensions thereof,

the crimped portions of the upper flange at 45 the extremities of the device engaging each other and interlocking to assist in holding the said extremities in positive associated relation, and means removably applied around the overlapped extremities for holding the latter in engagement.

3. An economizer and adapter for burners of the type specified, having an upper inwardly converged body with an upper flange inwardly inclined at a greater angle 55 than the body and crimped in upwardly inclined planes to strengthen the top of the economizer and also form flame and heat flues, the extremities of the body and flange being separably overlapped to modify the 60 diameter of the device as a whole, and fastening means separably applied around the overlapped extremities.

4. An economizer and adapter for burners of the type specified, having an inwardly converged body with a top flange inwardly inclined at a greater angle than the body, the extremities of the body being separably overlapped and provided with means removably applied therearound for holding 70 them in associated relation, the upper flange being regularly formed with corrugations at an angle of inclination relatively to the vertical to strengthen the top of the economizer and resist crushing or bending of the 75 same and also form flame and heat flues, the corrugations of the upper flange closely interfitting and forming a locking means when the extremities of the body are overlapped and preventing the said overlapped 80 extremities from slipping and thus providing for the use of a fastening means around the overlapped extremities of a simple character.

In testimony whereof I have hereunto set 85 my hand.

CHARLES M. FEIST.
